UNITED STATES PATENT OFFICE

ALFRED F. MASURY, OF NEW YORK, N. Y., ASSIGNOR TO THE RUBBER SHOCK INSULATOR CORPORATION, OF WILMINGTON, DELAWARE, A CORPORATION OF DELAWARE

STRUT CONSTRUCTION

Original application filed July 14, 1926, Serial No. 122,528. Divided and this application filed January 6, 1928. Serial No. 244,790.

The present invention relates to an improved form of strut for mounting a propeller shaft outwardly of the hull of a boat. This portion of the shaft receives severe 5 stresses during the rotation of the propeller, especially when the latter strikes floating objects or is out of water for a short while due to unusually rough water. Under ordinary operating conditions the propeller shaft is subjected to continual vibration by 10 reason of the unequal reactions on the several propeller blades due to faulty construction and slight irregularities in the pitch and lead thereof.

These vibrations and radial thrusts are transmitted directly to the hull through the struts and an object of this invention is to relieve the hull from these harmful strains. By cushioning the strut mounting, the vibration of the shaft is effectively deadened 20 and there results a construction which provides a strong shaft mounting and at the same time affords a hull which is free from the objectionable vibrations referred to 25 above.

The present application is a division of the application of Alfred F. Masury, Serial No. 122,528 filed July 14, 1926, for cushioning devices for marine propulsion. As set 30 forth above, the present invention has for an object, the provision of a strut construction which affords a mounting having sufficient strength and at the same time deadens the vibrations set up in the shaft and 35 impressed upon the hull.

Further objects of the invention will appear as the description proceeds and reference will now be had to the accompanying drawings wherein:

Figure 1 is a view in elevation, partly in section, showing a preferred form of the present invention.

Figure 2 is a front elevation, partly in section, showing the construction of Figure 1.

The hull of a boat is indicated generally at a , the planking therefor at a' , the ribs at a'' and the uprights between the ribs to support the deck at a''' . A suitable block a^4 is provided between certain of the ribs a'' for

mounting a portion of the yielding non-metallic means which secures the strut.

Between the block a^4 and the hull, a canvas and white lead seal a^5 is provided.

The strut or hanger b , carrying at one end 55 the propeller shaft c , extends through the hull and block a^4 and is provided with an enlarged end b' . Bolts d' secure the base d to the ribs adjacent the block a^4 and between the block a^4 and the strut b , a non-metallic ring e is provided. If desired, a 60 grummet e' may be provided to seat the cushioning ring e within the block a^4 and opening in the hull a .

Within the base d , a plate f is provided 65 which serves as a seat for the block of yielding non-metallic material g . A cap d^2 fits over the block of yielding material g and clamps the latter upon the plate f . The compression set up within the block by the clamping 70 of the block d^2 upon the plate f may be varied by means of securing bolts d^3 .

The enlarged end b' of the strut b is received within a suitably formed recess in the block g and when the cap is clamped 75 down upon the latter, the strut is held yieldingly in the desired position. The non-metallic cushioning ring e about the shank of the strut serves as an added strengthening element, as well as an effective seal between 80 the strut and the hull, and the resulting construction affords a mounting for the strut which is sufficiently strong to carry the propeller shaft although it is not so rigid as to transmit the objectionable vibrations from 85 such shaft to the hull.

The details of construction and arrangement which have been shown hereinbefore are not to be construed as limiting the invention, the scope of which is defined in the 90 appended claims.

I claim as my invention:

1. The combination with the hull of a vessel formed with an opening and a propeller shaft, of a strut formed with a bearing for 95 the propeller shaft and an enlarged end, the shank of the strut passing through the opening in the hull, yielding non-metallic material surrounding and engaging the shank within the opening to resist gyratory move- 99

ments, and means to secure the end of the strut within yielding non-metallic material under compression within the hull.

2. The combination with the hull of a vessel formed with an opening and a propeller shaft, of a strut formed with a bearing for the propeller shaft and an enlarged end, the shank of the strut passing through the opening in the hull, yielding non-metallic material surrounding and engaging the shank within the opening, a metallic housing section secured to the hull and formed with an opening through which the shank of the strut passes, another housing section bolted to the first named housing section and yielding non-metallic material under compression disposed within the housing and engaging the enlarged end of the strut.

This specification signed this 22d day of December A. D. 1927.

ALFRED F. MASURY.
